BY Walter N. Haskell,
his ATTORNEY.

UNITED STATES PATENT OFFICE

CHARLES F. KURTZ, OF ROCK ISLAND, ILLINOIS, ASSIGNOR, BY MESNE ASSIGNMENTS,
TO L. J. SHIELDS, OF ST. PAUL, MINNESOTA

COIN-OPERATED VENDING MACHINE

Application filed October 21, 1929. Serial No. 401,170.

My invention has reference to coin operated vending machines, and relates more specifically to certain improvements and attachments to a machine of that type which is set forth in an application filed by myself in the Patent Office of the United States on the twenty-ninth day of July, 1929, Serial No. 381,744. The purpose of the present invention is to provide means whereby any attempts to operate said machine by the use of slugs or other substitutes for the coin intended to be used in connection therewith will be interfered with and defeated.

It is a common practice to undertake the operation of coin controlled machines and the surreptitious removal of the contents thereof by the use of worthless metal checks of a suitable size and shape to cause the operation of the machine. Some of these are formed of a metal which will respond to magnetic influence, while others are of non-magnetic metal, and of special forms. One of these of type quite largely used is in the form of a brass disk of the size of a coin of established size for operating a machine, with an opening in its center. In the present invention means is provided for interrupting the movement of a coin or check of any kind that is introduced into the machine, at a point between the receiving slot and the coin handling devices, and interfering with its further progress if it is spurious. In the case of slugs or other devices which are thus arrested means of a magnetic character is provided for distracting such slug and diverting it from the regular course, for ejection from the machine. In the case of the disks with a central opening, a means is provided for detaining the same during the initial operation of the coin handling devices, so that the same will be held from operation therewith, and also discharged from the machine without effecting the release of any of the contents thereof.

The particular construction, arrangement, and operation of the various parts of the invention will be more fully understood from the following specification, taken in connection with the accompanying drawings, in which only so much of the original machine

is shown to disclose the application of the novel devices thereto. In said drawings:

Fig. 1 is a vertical medial section through the operating parts of a vending machine such as is set forth in said former application, with the parts in normal position. 55

Fig. 2 is a similar view with the parts in operative position.

Fig. 3 is a rear elevation of the mechanism included in the present invention, in connection with appurtenant parts of the machine. 60

Fig. 4 is a horizontal cross-section on the line 4—4 of Fig. 2.

Fig. 5 is a detail of the cams 19.

Fig. 6 is a detail of one of the disks. 65

The reference number 1 indicates a casing, in which is fixed a front plate 2. Within the machine is a frame 3, above which is supported a parcel magazine 4, just beneath which is a parcel discharge frame 5. Rockingly supported at its rear end is a shaft 6, the front end of which extends through an opening in the plate 2, and is provided with a thumb-turn 7. Fixed to said shaft just in rear of the plate 2 is a disk 8, containing a coin-way 9, in line with a coin-slot 10 in a plate 11 of the casing 1. On the edge of the disk 8 is a tooth 12, for engagement by a pawl 13, to hold the disk from rotation in the direction indicated by the arrow in Fig. 3. Said tooth is normally spaced from said pawl a little distance, as shown in said Fig. 3, permitting an initial rotation of the disk before the tooth encounters the pawl. The disk 8 is also provided with means for preventing a return movement thereof during its primary rotation, which is not involved in the present invention. 70 75 80 85

In rear of the disk 8 is a circular plate 15, 90 slidable on the shaft 6, and held from rotation by side rods 16 passing through perforated ears 17 on the sides of the plate 15. Said plate is held yieldingly in contact with the disk 8 by a coiled spring 18 on the shaft 6. On the inner face of the disk 8 is fixed a pair of spiral cams 19, operating in arc-shaped channels 20 in the plate 15, and pivoted to the upper edge of the plate 15 is a plate 21, provided at its rear end with plung- 95 100

er devices 22, operable in the discharge frame 5, to cause a successive removal of parcels contained in the magazine 4. The mechanism hereinbefore described is substantially the same as that set forth in said application now on file.

On the inside of the plate 2, just beneath the plate 11, is a chute 25, forming a passage for a coin between the slot 10 and coin pocket in the disk 8. Secured in a recess in the inner face of the plate 2 is a spring-plate 26, the upper end of which is bent into a stop 27, just beneath the chute 25. Said stop is held normally in position to intercept a coin or other article passing into the chute, and is removed therefrom by the forward movement of the plate 26, into the position shown in Fig. 2. This is accomplished by means of a pin 28 on the inner face of the plate 26, engaged by a cam 29 on the outer face of the disk 8. Upon the thumb-turn 7 being operated in a clock-wise direction, the disk 8 is moved in the same direction, causing the cam 29 to force the pin 28 and plate 26 outwardly and clearing the passage in the chute. In case a coin of recognized value is being held in the chute it immediately drops downwardly into the coin-pocket 9, and upon a continued rotation of the disk 8, raises the pawl 13, permitting a continued rotation of the disk, and resulting in the discharge of the coin into the lower part of the casing.

At one end of the chute 25 is supported a small magnet 30, which attracts a slug or spurious coin containing iron or similar metals, and draws them in the direction of the magnet, the chute being open at that end, and the magnet not being of sufficient strength to support the object, it drops downwardly into a chute already provided in the machine, shown at 31, by means of which it is ejected from the machine.

To the rear wall of the chute 25 is attached a pair of ears 32, between which is pivoted an arm 33, to the upper end of which is connected a pin 34, adapted for insertion into the passageway of the chute through an opening in said rear wall thereof. The pin is held normally in withdrawn position, as shown in Fig. 1, by means of a coiled spring 35 on said pin, bearing against the head of the pin in one direction and against the wall of the chute in the other direction. The arm 33 is projected upwardly into a cam-end 36, and the lower end of said arm carries a tooth 37, for engagement with a lug 38 supported on a plate spring 39, fixed at one end to a bracket 40 on the plate 15. As the disk 8 is turned the plate 15 moves inwardly, rocking the arm 33, and causing the pin 34 to enter the central opening of a perforated disk, such as is shown at 41, if such a disk is contained in the chute 25. If a more solid object is contained in said chute the spring support of the lug 38 permits it to slide beneath the

tooth on the end of the arm 33, without rocking the same.

When the upper end of the arm 33 is moved forwardly the cam-end 36 slides beneath a catch 42 pivoted beneath ears 43 fixed to the upper part of the chute 25, until the end of said arm is finally engaged by said catch, as shown in Fig. 2. This occurs during the initial rotation of the disk 8, and as said disk continues to rotate the plate 15 is carried farther to the rear, the lug 38 passing beneath the end of the arm 33, as before mentioned, and at approximately the same time the catch 42 is released by means of a wire arm 44 attached thereto, and having a downwardly bent arm in engagement with an abutment 45 on the plate 15. The continued inward movement of said plate forces said arm rearwardly, raising the catch 42, and permitting the spring 35 to return the pin 34 and arm 33 to their former positions. If one of the disks 41 has been detained by the pin 34 the withdrawal of the pin permits it to drop, but by this time the disk 8 has been moved so far that the disk 41 cannot enter same, but is either carried round the edge of the disk 8 into the chute 31, or falls into the large end of the coin-way 9, from which it is dumped into the chute 31 upon the return of the disk 8 to its former position. By means of a weight 46 on the downwardly bent portion of the wire arm 44 said arm and the catch 42 are at all times retained operative positions.

There is a possibility of a coin which is released from the chute 25 being thrown to the side of the coin pocket by a too rapid movement of the disk 8, and to prevent such a mishap the edges of the cams 19 are provided with enlargements 47, as shown in Fig. 5, which retard the initial movement of the disk.

What I claim, and desire to secure by Letters Patent, is:—

1. A vending machine, comprising a casing provided with a coin entrance, a coin handling mechanism in said casing having a coin receiving space in line with said entrance, means for arresting a coin in its movement from the entrance to said receiving space, means for engagement with a spurious coin while arrested, and means for operation of said last-named means coincidently with the operation of said coin handling mechanism.

2. A vending machine, comprising a casing provided with a coin entrance, a coin chute in line with said coin entrance, a coin handling mechanism provided with a coin space in line with said chute, and movable out of line therewith upon the operation of said coin handling mechanism, a stop at the inner end of said chute releasable on the initial movement of said coin handling mechanism, and means for retaining a spurious coin in said chute after the stop has been released,

and until said coin space is out of line with the chute.

3. A vending machine of the class described, comprising a casing provided with a coin entrance, a coin chute in line with said entrance, a coin handling mechanism provided with a coin space in line with said chute, and movable out of line therewith upon the operation of the coin handling mechanism, means for arresting the movement of a coin in said chute, means for engagement with a perforated disk in place in said chute, means for actuating said last-named means upon the movement of the coin handling mechanism, and means for releasing said engaging means after said coin space has been moved out of line with said chute.

4. In a vending machine of the class described, a casing provided with a coin entrance, a parcel magazine therein, a coin disk rotatably supported in said casing, provided with a coin space in line with said entrance, a parcel discharging mechanism, means operated by said coin disk for actuating said parcel discharging mechanism, a coin arresting device between said coin entrance and said coin space, and means for diverting a spurious coin held by said arresting device from entrance into said coin space.

5. In a vending machine of the class described, a casing provided with a coin entrance, a coin receiving and delivery wheel rotatably mounted in said casing, means on the outside of the casing for operating said wheel, means for locking said wheel from rotation following an initial movement thereof, releasable by a coin in said wheel, means for arresting a coin in its passage from the coin entrance to said wheel, releasable upon the movement of said wheel, and means for preventing a spurious coin which is arrested by said last-named means from being received by said wheel.

6. In a coin operated vending machine, a casing provided with a coin entrance, a coin receiving member movably supported in line with said entrance, means for arresting a coin in its passage to said receiving member, and means controlled by the movement of said coin receiving member for preventing the delivery of spurious non-magnetic coins to said coin receiving member.

7. In a coin operated vending machine, a casing provided with a coin entrance, a coin handling member rotatably supported in said casing, and provided with a coin space in line with said entrance, a parcel magazine and means associated therewith for discharge of parcels therefrom, a slide member operatively connected with said parcel discharge means, and operable by said coin handling member in its movement, a coin guide between said coin entrance and coin space, provided with an opening in its rear wall, means for arresting the movement of a coin in said guide, an

arm pivotally mounted in rear of said coin guide, a pin carried by said arm, adapted to enter said guide, means for holding said pin yieldably in withdrawn position, a trip mechanism carried by said slide member having a yieldable engagement with said arm, and means for locking said arm with the pin in place in said coin guide, releasable upon a continued movement of said slide member.

8. In a coin operated vending machine, a casing and coin entrance therein, a coin disk rotatably mounted in said casing, and provided with a coin space in line with said entrance, a magazine for the support of a plurality of parcels in vertical column, a parcel discharging apparatus associated therewith, an active member operatively connected with said discharging apparatus, means on said coin disk for the operation of said active member, a guide between said coin entrance and coin space, a detent pin movable into said guide, means for holding said pin normally withdrawn, a pivotally supported arm connected with said pin, a spring-pressed trip on said active member engageable with said arm to actuate said pin, a catch engageable with said arm, to hold said pin in position in said guide, provided with a release arm engageable by said active member upon a continued movement thereof, and means for arresting the movement of a coin in said guide, releasable upon the initial movement of said coin disk.

In testimony whereof I affix my signature.
